UNITED STATES PATENT OFFICE.

T. TRASK WOODWARD, OF DECATUR, ILLINOIS, ASSIGNOR OF ONE-HALF
TO JOHN F. FLOOD, OF SAME PLACE.

VAPOR-BURNER.

SPECIFICATION forming part of Letters Patent No. 254,185, dated February 28, 1882.

Application filed December 15, 1881. (No model.)

To all whom it may concern:

Be it known that I, T. TRASK WOODWARD, a citizen of the United States, residing at Decatur, in the county of Macon and State of Illinois, have invented a new and useful Improvement in Vapor-Burners, of which the following is a specification.

My invention relates to improvements in vapor-burners for stoves; and it consists, first, 10 in a common gas-pipe **T** as a generator, set in a vertical position and filled with pebbles to occupy space; second, a flat holding disk or plate adjustably attached to the top end of the **T** and adapted to hold the tube or burner, with 15 a series of jets above and below the plate; third, an iron rod fitted loosely into the horizontal portion of the fluid-conducting pipe, to serve as a filler and to regulate the pressure or flow, all arranged to operate as hereinafter described. 20 I attain these objects by the device illustrated in the accompanying drawings, in which—

Figure 1 is a vertical section on the line *x x*, Fig. 3. Fig. 2 is an end view of the iron rod. Fig. 3 is a top view.

25 Similar letters refer to similar parts throughout the several views.

A represents the generator, and is a common gas **T** pipe filled with pebbles to occupy space.

30 **B** is the holding disk or plate, and is secured to the top end of the generator **A** by a screw, **b**, which passes through the plate into a plug fitted into the generator.

35 **C** is the burner, and is provided with two rows of holes, **c c'**, through which the flame passes, and has a shoulder, **a**, formed near its upper end. The smaller part or body of this tube is passed down through a central hole, **b'**, in the plate **B**, and is suspended by the shoulder resting upon the top of the plate, the lower 40 end of burner reaching to within about one-half inch of the orifice **d** of the valve **D**, leaving space enough for the air to mingle with the vapor emitted from the orifice and supply the necessary oxygen within the burner. A cap, 45 **i**, is placed on the upper end of the burner, which forces the flame out through the rows of holes, one row of holes being above the plate and the other below it. The flame spreading from the lower row of holes envelops the generator, thereby keeping the supply equal to the

consumption. The disk or plate **B** accomplishes two purposes—first, as a holder for the burner, and, second, as a divider of the flame, by means of which a perfect blue flame is obtained, through which no smoke or unconsumed vapor can escape. The lower flames burn off all smoke or soot created by burning fluid in the generating-cup to start the burner. 55

The supply-pipe **E** is screwed into the side opening of the generator, as shown at **e**, and from thence leads to the tank above, as in others of its class. Within the parallel section of the pipe attached to the generator is placed an iron rod, **F**, whose diameter nearly equals that of the interior of the pipe. One of its sides is flattened to allow the fluid to pass through into the generator. The inner end of this supply-pipe is closed by a plug, **f**, screwed into it, and having a small hole through it for the fluid to pass through and to serve as a stop to the rod **F**. This rod serves as a filler as well as a regulator of the pressure of the fluid, which holds it in place. The length of rod depends upon the elevation of the tank above the burner, and should be proportioned accordingly. 70 The rod is also a heat-conductor, and materially assists in generating vapor. 75

Within the tank or pipe (whichever may be the more convenient) wool is placed in such a position that the fluid must pass through it, thereby preventing the passage of sediment to the generator. The construction is so simple that any one can readily understand how it is manipulated. Should the valve-orifice become stopped from any cause whatsoever, loosen the 80 screw **b** and swing the holding-plate **B** to one side, and free access is had to the same. 85

It is obvious that the burner **C** may be fitted either tight or loosely into the hole **b'** of the plate. In either case it can be easily cleaned 90 by simply removing the cap **i** and passing a cloth or brush down through it.

I am aware that the valve, drip, or generating cup and tank elevated above the burner are old. I therefore do not claim these elements broadly. 95

Having thus fully described my invention, what I claim, and desire to secure by Letters Patent, is—

1. In combination with the holding-plate **B**, 100

the burner C, fitted into the central hole, *b'*, of the plate, and suspended therefrom by the shoulder or offset *a*, and provided with a row of holes, *c*, above the plate and a row of holes, *c'*, below the plate, substantially as shown, and for the purpose described.

2. In a vapor-burner, the combination of the generator A, the holding-plate B, secured thereto by screw or rivet, and burner C, having two

rows of holes, one above and one below the plate, to the flame issuing from the lower row of holes being spread by the plate and compelled to continually envelop the generator, as herein set forth.

T. TRASK WOODWARD.
